UNITED STATES PATENT OFFICE.

EDWARD T. LAGERHOLM, OF GREENVILLE, SOUTH CAROLINA.

RETRIEVER FOR CIRCULAR TYPEWRITER ERASERS.

Application filed September 14, 1922. Serial No. 588,216.

To all whom it may concern:

Be it known that I, EDWARD T. LAGERHOLM, a citizen of the United States, residing at Greenville, in the county of Greenville and State of South Carolina, have invented certain new and useful Improvements in Retrievers for Circular Typewriter Erasers, of which the following is a specification.

10 This invention relates to office appliances and has special reference to a retriever for typewriter erasers.

It is a well understood fact that typists are continually mislaying and losing the 15 small round erasers that are commonly employed in making erasures on typewritten documents.

One important object of this invention is to provide an improved and novel device 20 which may be placed on the machine or desk where such typewriting is being done and which will hold the eraser when not in use in a readily accessible position and will automatically return said eraser to such 25 position as soon as the eraser is released after using.

A second important object of the invention is to provide an improved form of eraser retriever wherein the eraser will be 30 held in elevated position with its flat side toward the typist.

With the above and other objects in view as will be hereinafter apparent, the invention consists in general of certain novel 35 details of construction and combinations of parts hereinafter fully described, illustrated in the accompanying drawings and specifically claimed.

In the accompanying drawings like characters of reference indicate like parts in the 40 several views, and:

Figure 1 is a side elevation of the improved retriever.

Figure 2 is a vertical median section therethrough.

Figure 3 is a front elevation of the device partly in section.

In the construction of this invention, there 50 is provided a housing which consists of a substantially cylindrical portion 10 supported on a base 11 provided with an attaching flange 12 wherethrough screws 13 may pass for attachment of the device to a table, or typewriter. Through the hollow

cylindrical portion 10 passes a shaft 14 55 whereon is mounted a hollow drum 15. Within the drum 15 is a spiral spring 16, one end of which is secured to the shaft 14 while the other end is secured to the periphery of said drum. On the drum is wound 60 a cord 17, the winding of the cord being in opposite direction to the spring 16 so that when the cord is drawn off the spring will be wound up at this time to retract the cord. Extending radially from one side of 65 the housing 10 is a hollow tapering boss 18, the smaller end of the boss being toward the center of the housing. From the larger end of this boss extends a lateral flange 19 curved upward as at 20 at its periphery 70 and the cord 17 runs through this boss and is provided at its outer end with a tapered plug 21 which fits the boss 18 and has on its outer end an internally threaded hollow 75 boss 22 of proper size to fit within the opening in the center of the circular eraser 23. A screw 24 is threaded into this hollow extension and holds the eraser in position. From an inspection of the drawings it will be seen that when the plug 21 is drawn into 80 the hollow boss the eraser 23 will rest against the curved periphery 20 of the flange 19. The edges of the eraser will thus be spaced from the housing and the eraser will face the operator who, when it is desired to use 85 the same, can grasp the eraser and draw it into position for use. When through with the eraser the operator has simply to let go of the same wherupon, by action of the spring 16, it will fly back into position, as 90 shown.

There has thus been provided a simple and efficient device of the kind described and for the purpose specified.

It is obvious that minor changes may be 95 made in the form and construction of the invention without departing from the material spirit thereof. It is not, therefore, desired to confine the invention to the exact form herein shown and described, but it is 100 desired to include all such as properly come within the scope claimed.

Having thus described the invention what is claimed as new, is:—

In a retriever for typewriter erasers, a 105 base, a cylindrical housing carried by said case, a spring wound drum within said housing, a hollow boss projecting from one

side of the housing, a cord wound on said drum and extending through said boss, a lateral flange having an upturned edge at the outer end of said hollow boss, a plug fixed on the free end of said cord and adapted to fit within the opening of a typewriter eraser, and a screw engaging said plug to hold the eraser releasably thereon, said boss and plug being correspondingly

tapered whereby the plug will fit within the 10 hollow boss.

In testimony whereof I affix my signature in presence of two witnesses.

EDWARD T. LAGERHOLM.
